Holding Corporation, Syracuse, N. Y., a cor-
poration of New York

Application September 23, 1938, Serial No. 231,385

1 Claim. (Cl. 101—301)

This invention relates to machines for marking shoe upper sections or similar pieces of sheet material.

In the manufacture of shoes, particularly women's shoes, it is customary to apply ornamental designs to the shoe uppers, as by stitching, perforating or embossing. Present fashions demand that shoe uppers be made of leather, textile fabrics such as silk, satin or velvet, and various other kinds of sheet material. Usually, the ornamental designs are applied to the cut-out sections of the uppers before they are assembled in the shoe; and in the case of stitching, the designs are first marked on the shoe uppers and the marked designs are then followed in the stitching. In accordance with the customary practice, the design may be impressed upon the shoe upper section, or similar article of sheet material, by a marking plate, on which the desired pattern is formed by bosses punched from the material of the plate and disposed in lines, rows or other arrangements to delineate the pattern. The marking plate may then be pressed against a transfer sheet having its pigmented surface disposed against the shoe upper section or other piece of work to be marked, and the pattern displayed by the bosses will then be printed or impressed on the work. A similar method may be used without the transfer sheet for merely embossing a piece of leather, in which case the marking plate will be embossed in accordance with the desired design, or for perforating the work, in which case the marking plate will be made with bosses in the form of cutting punches of such shape and arrangement as to cut holes or perforations in the work, shaped and arranged according to the desired design.

Printing or marking, perforating and embossing, whether used separately or in various combinations at the same time, are all included in the expression "marking" as herein used; and the term "marking plate" is used to designate the plate for applying the design to the work whether the plate is constructed for printing from a transfer sheet, or for perforating, or for embossing, or for any combination of these operations.

The principal objects of the present invention are to provide a marking machine for carrying out the aforementioned operations, to provide means for securely holding a marking plate accurately in position with respect to the material to be marked, and to provide a marking machine which is of simple design and of strong and dur-

able construction, which is sufficient and reliable in operation and in which means are provided for using interchangeable marking plates which may be readily and accurately positioned.

Further objects relate to various features of construction and will be apparent from a consideration of the following description and accompanying drawings, wherein:

Fig. 1 is a top plan view, with parts broken away and shown in section, of a marking machine constructed in accordance with the present invention;

Fig. 2 is a side elevation of the machine shown in Fig. 1, but with certain parts removed;

Fig. 3 is a top plan view of a marking plate adapted for use in the machine shown in Fig. 1;

Fig. 4 is an enlarged section on the line 4—4 of Fig. 3;

Fig. 5 is an enlarged section on the line 5—5 of Fig. 1; and

Fig. 6 is a top plan view, on a reduced scale, of one form of gauge plate for use in positioning right and left quarters.

The embodiment chosen for illustration comprises a base or bed 10 (Figs. 1 and 2) provided with a pair of spaced rearwardly extending arms 11, the outer ends of which support a pair of links 12. A second pair of links 14 is pivotally connected to the opposite sides of the base 10 adjacent to its rear edge, the links 12 and 14 being pivotally connected at their upper ends with a marking plate carrier or platen, designated by the numeral 15, and being effective at all times to support the platen 15 for movement toward and away from the upper face of the base 10 and in parallel relation thereto.

The upper face of the base 10 supports a detachable gauge plate 17 (Fig. 6) comprising a relatively heavy piece of fiber board or the like suitable sheet material (Figs. 1, 2 and 6), which is provided with an elevated guide 18 against which right and left shoe upper quarters are arranged, as indicated by the dot and dash lines of Fig. 1. In order to hold the gauge plate 17 in fixed position, its inner margins, adjacent to its rear corners, are formed with apertures 19 which receive positioning lugs 20 projecting upwardly from the rear of the base 10, as shown in Fig. 2. The front end of the gauge plate is secured in fixed position by a pair of clamps 21, each of which is formed with a stem 22 extending downwardly through an aperture formed in the base 10, and a coil spring 23 is circumscribed about each stem so as yieldingly to urge the clamps downwardly to grip the gauge plate 17, as illus-

trated in Fig. 2. In order to remove or replace the gauge plate it is merely necessary to raise the clamps 21 and turn them aside, thereby permitting the front end of the gauge plate to be moved toward or away from the base 10.

The platen 15 is preferably of aluminum or the like relatively non-magnetic material, and is formed with a pair of spaced elongate slots 30 (Fig. 2) at its forward portion, and a second pair of elongate slots 31 (Figs. 2 and 5) at its rear portion. A pair of electromagnets 32 and 33 are rigidly secured to the platen by fastening elements or clamps 35. Each of the electromagnets comprises a U-shaped core or pole piece 15 having a coil circumposed about each leg at a point spaced from its end, the legs of the magnet 32 extending into the slots or openings 30, and those of electromagnet 33 extending into the slots or openings 31. The ends of the cores 20 are preferably perfectly flat and are disposed in close proximity to the plane of the bottom surface of the platen 15, as illustrated in Fig. 5.

At each side of the electromagnet 30 there is provided a forwardly extending bracket 38, each 25 of which rotatably supports one end of a handle 39 by means of which the platen 15 may be swung from inoperative position, as shown by the full lines of Fig. 2, to an operative position relative to the base 10, as indicated by the broken lines of Fig. 2. The platen 15 is normally maintained in elevated or inoperative position by a tension spring 40, one end of which is secured to the lower pivot 41 of one of the links 12, and its other end is secured to a pin or lug 42 carried by 35 one of the links 14. A stop 43, projecting outwardly from the base 10, is provided to limit the upward movement of the platen 15.

The particular machine here shown is designed to operate upon right and left quarters simultaneously, and accordingly the gauge plate 17 is provided with a guide member 18 shaped and arranged to position the quarters in a predetermined fixed position so as to be operated on by the marking devices presently to be described, it 40 being understood that if desired the construction and arrangement may be such as to accommodate a different number of pieces and/or different shapes, such for example as vamps. As here shown, the marking device comprises left and right marking plates 50 and 51, respectively (Fig. 5), each of which consists of a relatively thin piece of magnetic sheet material, preferably having the size and shape of the quarters to be marked and formed with marking projections or 45 studs 52 (Figs. 3 and 4) delineating the marking or design to be applied.

In preparing the machine for operation the marking plates 50 and 51 are first positioned on the gauge plate 17 with their studded sides lowermost, as indicated by the dot and dash lines of Fig. 1, and after having connected the electromagnets with a suitable source of electric current, the plate 15 is swung forwardly and downwardly into operative position, as indicated by 60 the broken lines of Fig. 2, whereupon the electromagnets are brought into position to pick up and firmly hold the marking plates in fixed position against the underside of the platen 15, as 65 illustrated in Fig. 5.

Where, as here shown, the marking plates operate in conjunction with a pigmented transfer sheet, the latter is supported in operative relation to the marking plates, and to this end there is provided at one side of the platen 15 a pair of 70 spaced brackets 55 (Figs. 1 and 5) which are

formed with slots 56 (Fig. 5) provided open bearing members which rotatably support a shaft or spindle 57 to which one end of a transfer web 58 is suitably fastened. At corresponding positions on the opposite side of the platen 15 there is provided another pair of spaced brackets 60 having slots 61 (Fig. 5) providing a second pair of opening bearings which rotatably support a shaft or spindle 62 to which the opposite end of the web 58 is suitably fastened. The brackets 55 and 60 are formed with depending arms 64 (Figs. 2 and 5), the lower end of which extends below the under surface of the platen 15, and adjacent to their lower ends each pair of arms is formed with aligned openings which provide bearings for 10 rotatably supporting guide rolls 65 and 66, the construction and arrangement being such that the web 58 is held in closely spaced relation to the operating face of the marking plates, as illustrated in Fig. 5. One end of the transfer web is 20 wound up more or less upon one of the shafts 57 or 62, and its intermediate portion extends around the adjacent guide rolls, beneath the platen and thence about the other guide roll to the other shaft to which it is fastened. 25

In order to hold the shafts 57 and 62 against free rotation, there is provided for each end of the shafts a spring finger or arm 68 (Fig. 1), the inner end of which is secured to the platen 15 preferably by a single screw 69 or the like fastening element, which permits the spring arm to be flexed upwardly and swung to one side. The outer or free end of each spring arm is preferably curved so as to engage the projecting end of the associated shaft, as shown in Figs. 1 and 5, thus 35 providing a friction brake effective to prevent free rotation of the shafts. With this construction and arrangement the spring arms not only 40 yieldingly hold the shafts in position within the bearings, but also are effective to hold the web in adjusted position.

In order to adjust the web 58 so as to present fresh surfaces thereof to the marking plates, the inner ends of the shafts 57 and 62 are provided with hand wheels 71 and 72 (Fig. 1), by means of 45 which the shafts may be rotated. In order to remove or replace the shafts 57 and 62 together with the transfer web 58, it is merely necessary to flex the spring arms upwardly and swing them 50 out of the way.

In using a machine constructed in accordance with the present invention, the marking plates are first attached to the platen as above described, and thereafter right and left quarters may be positioned against the guide member 18, as indicated by the dot and dash lines of Fig. 1, and by grasping the handle 39 the platen 15 may be swung downwardly, as indicated by the broken lines of Fig. 2, to mark the quarters simultaneously. The marked quarters are then withdrawn 60 and unmarked quarters are substituted and the operation continued, it being understood that the electromagnets 32 and 33 are effective firmly to hold the marking plates 50 and 51 in position during the marking operation, notwithstanding the shocks to which these parts are subjected. If it be desired to mark a different type of quarter, or any other type of sheet material, the gauge plate 17 and marking plates 50 and 51 may be removed and others may then be substituted therefor in the manner previously explained. 70

While I have shown and described one desirable embodiment of the invention, it is to be understood that this disclosure is for the purpose of illustration and that various changes in shape, 75

proportion and arrangement of parts, as well as the substitution of equivalent elements for those herein shown and described, may be made without departing from the spirit and scope of the invention as set forth in the appended claim.

I claim:

The method of marking shoe upper elements and like materials in a machine of the type having stationary and movable members, including 10 magnetic means on the movable member and gauge means on the stationary member for positioning the element to be marked, which method comprises positioning on the stationary member a marking plate of magnetic material having an

edge portion conforming to that of the element to be marked so that said edge portion is contiguous to the gauge means, actuating the movable member to bring it into operative relation with the stationary member so that said magnetic 5 means is brought into position to pick up and firmly hold said marking plate in fixed position against the under side of said movable member, thereafter positioning the element to be marked against said gauge means, and actuating the 10 movable member so as to bring the marking plate into operative engagement with said element, thereby accurately to apply markings to the same.

CLAUDE D. TILSON.
